(57) **CLAIM**

We claim the ornamental design for a microphone, as shown and described.

DESCRIPTION

FIG. 1 is a perspective view of a microphone;
 FIG. 2 is a front view of the microphone;
 FIG. 3 is a rear view of the microphone;
 FIG. 4 is a left side view of the microphone;
 FIG. 5 is a right side view of the microphone;
 FIG. 6 is a top plan view of the microphone; and,
 FIG. 7 is a bottom plan view of the microphone.
 Portions of the drawings shown in broken lines form no part
 of the claimed design.

1 Claim, 7 Drawing Sheets(56)
